LIGHTING FIXTURE

John Ansley Keller, Creamery, Pa., assignor to Heavy
Light Mfg. Corp., Fairview Village, Pa.

Filed Mar. 7, 1973, Ser. No. 338,790

Term of patent 14 years

Int. Cl. D26—05

U.S. Cl. D48—4 B

Fig. 1

Fig. 5

Fig. 4

Fig. 2

Fig. 3

Fig. 6

FIG. 1 is a top view of a lighting fixture, showing my new design;

FIG. 2 is a side view thereof;

FIG. 3 is a front view thereof;

FIG. 4 is an end view as seen from the surface wall to which the lighting fixture becomes attached;

FIG. 5 is a bottom view of the lighting fixture; and

FIG. 6 is a side view of the lighting fixture in an alternate position.

The wall surface is shown in broken lines for illustrative purposes only.

I claim:

The ornamental design for a lighting fixture, substantially as shown and described.
